FIRST-AID KIT

Edmund M. Campbell, Pittsburgh, Pa., assignor
to Mine Safety Appliances Company, Pittsburgh, Pa., a corporation of Pennsylvania

Application January 26, 1945, Serial No. 574,761

3 Claims. (Cl. 224—50)

1

This invention relates to first-aid kits, and more particularly to those kits in each of which the items of first-aid are packaged in a plurality of light boxes, generally of uniform length and breadth, and commonly referred to as unit containers.

It is among the objects of this invention to provide a first-aid kit which has an outer case that can be permanently attached to a support, which has a portable unit removably housed in the case, and in which first-aid unit containers are clamped in the portable unit in such a manner that as individual boxes are removed the remaining boxes remain clamped in place.

In accordance with this invention a frame is provided which has spaced end walls and an open side. The end walls may be substantially parallel plates that are spaced apart by side members at three sides of the frame. Between the ends of the frame is an intermediate member, such as a plate substantially parallel to the end plates, that is movable back and forth between them. This movable plate is held in the frame and guided therein by means of the side members. The movable plate is constantly urged toward one of the end walls of the frame so as to enable it to clamp between itself and that wall a stack or row of first-aid boxes each containing one or more items of first aid. Preferably, two opposite side members of the frame are in the form of channels in which are disposed coil springs that are connected to the clamping plate and to the end wall toward which it is biased. When it becomes necessary to use one of the first-aid boxes it can be removed from the frame by merely pulling it out of the open side of the frame. The springs then will move the clamping plate to take up the space left by the removed box, whereby the rest of the boxes again will be clamped in the frame. It is preferred that the springs not be capable of moving the clamping plate all the way to the end of the frame, so after several of the boxes have been removed from the frame the plate will no longer clamp the rest in position. This makes it necessary to replace the used boxes before the frame has been completely emptied. The top of the frame is provided with a handle to permit it to be lowered into an open top container which has a closure for making it watertight. This case is adapted to be permanently mounted in any desired location. When an accident occurs requiring first aid, the case is opened and the frame with the first-aid boxes therein lifted from it and carried to the scene of the accident.

The preferred embodiment of the invention is

2

illustrated in the accompanying drawings in which Fig. 1 is a side view of the frame filled with first-aid boxes and sealed in a case shown in vertical section, and Fig. 2 is a perspective view of the frame alone.

Referring to Fig. 1 of the drawings, a watertight case is formed from a rectangular container having an open upper end normally closed by a removable flanged cover 2. The cover is provided interiorly with a rubber sealing gasket 3 that rests on top of the container and is held between the cover flange and a flanged member 4 attached to the lower surface of the cover. Although the cover may be clamped on the container in any suitable manner, it is preferred to use a toggle-like clamp of well known construction at each end. The link 6 of one of these clamps is pivotally connected to a hook 7 mounted on one end of the closure and bent over the top of the link to permanently connect the link to the hook so that this clamp will serve the double purpose of hinge and fastener. On the other hand, the link 8 of the other clamp can be lifted from an open hook 9, mounted on the opposite end of the cover, when the clamp is opened. Mounted on top of the cover is a handle 10 for raising it when it is desired to open the case. The case may be provided with any suitable means for rigidly mounting it on a support, such as on the body of a vehicle.

It is a feature of this invention that a plurality of first-aid boxes 12, containing compresses, bandages, iodine, ammonia inhalants, etc., are housed in the case in such a manner as to be removable therefrom as a portable unit. For this purpose a frame is removably disposed in the case. This frame has upper and lower end walls formed from rectangular plates 13 and 14 that are spaced apart and rigidly positioned parallel to each other by means of three side members. The side members 16 at the opposite ends of the plates preferably are in the form of channels welded to the end plates with their flanges projecting inwardly toward each other. Between these two channels 45 the rear edges of the plates are connected by a third side member 17 which may be a flat strip of metal having its ends bent over the end plates and welded thereto. The upper plate may be provided with a notch 18 through which this member extends, but the lower plate is shown narrower than the upper one and therefore without a notch. Channels 16 are spaced just far enough apart to permit the first-aid boxes to be inserted between them and moved back against member 17.

Between the ends walls of the frame there is an intermediate or clamping plate 20 that is movable up and down in the frame. This plate is held in the frame by providing its ends with pairs of notches 21 for loosely receiving the flanges of channels 16. The back of the plate likewise may be provided with a slot or notch 22 through which the rear side member 17 extends. The side members thus guide the clamping plate in its vertical movements. Disposed in each channel is a coil spring 23 for urging the clamping plate toward one end of the frame. Preferably, the springs are above this plate with their upper ends connected to top plate 13 and their lower ends connected to tongues 24 integral with the clamping plate and projecting into channels 16. These springs lift the clamping plate toward the top plate. By pressing the clamping plate downwardly a stack of first-aid boxes 12 can be placed on it, and when the plate is released the springs will cause it to press the boxes up against the top plate of the frame, whereby the boxes are held in place by the clamping action of the two plates. The top plate is provided with a folding handle 26, and the entire unit fits snugly inside of the case.

When an accident occurs requiring first-aid treatment, the case is opened and the frame with the first-aid boxes therein is lifted by its handle from the container 1 and carried to the scene of the accident. The boxes containing the desired items of first aid are then pulled out of the frame through its open front side, and the springs immediately raise the clamping plate so that it will continue to clamp the remaining boxes against the top plate. If any useful material is left in the boxes that were removed, they can be replaced in the frame by merely moving the clamping plate downwardly to make room for them. It is preferred that the springs lift the clamping plate only about half way up the frame, as shown in Fig. 2, so that when the plate reaches that level it no longer will clamp boxes in the frame. This is desirable because it forcefully calls attention to the fact that half of the boxes have been used up and the frame should therefore be restocked with new boxes as soon as possible in order to replenish the kit.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A first-aid kit comprising substantially parallel end members, a pair of oppositely disposed side channels spacing the end members apart, a plate between and substantially parallel to said end

members and movable back and forth between them, oppositely disposed edges of said plate being provided with pairs of notches for loosely receiving the flanges of said channels to slidably retain the plate between the channels, a side member connected to edge portions of said end members substantially midway between said channels, another edge of the plate being provided with a notch for loosely receiving said side member, and coil springs disposed in said channels with their ends connected to one of said end members and to said plate to clamp between said end member and plate a stack of first-aid boxes removable from between said channels away from said side member.

2. A first-aid kit comprising substantially parallel end plates, a pair of oppositely disposed side members spacing said plates apart and connected to two opposite edge portions thereof, a third side member connected to edge portions of the plates between said opposite edge portions, a clamping plate between and substantially parallel to said end plates and provided with openings for loosely receiving all three side members to slidably retain the clamping plate in position, springs pulling the clamping plate toward one of said end plates to clamp between said one end plate and clamping plate a stack of first-aid boxes removable from between said pair of side members away from said third side member, and a handle attached to one of the end plates for lifting the kit.

3. A first-aid kit comprising substantially parallel end members, a pair of oppositely disposed side members spacing the end members apart and each being provided with a pair of spaced substantially parallel flanges, a plate between and substantially parallel to said end members and movable back and forth between them, the plate having tongue portions projecting between said spaced flanges, coil springs between said spaced flanges with their ends connected to said tongue portions and to one of said end members to clamp between said end member and plate a stack of first-aid boxes removable from between said side members, and a handle attached to one of the end plates for lifting the kit.
